CLAIM

The ornamental design for a maternity brassiere closure, as shown and described.

DESCRIPTION

FIG. 1 is a front elevational view of a maternity brassiere closure showing my new design;

FIG. 2 is a rear view thereof;

FIG. 3 is a right side elevational view thereof, the left side view being mirror symmetrical thereto;

FIG. 4 is a top view thereof; and,

FIG. 5 is a bottom view thereof.
